UNITED STATES PATENT OFFICE.

HORACE ESTABROOK, OF PATERSON, NEW JERSEY.

RAILWAY WEIGHING-SCALE.

SPECIFICATION forming part of Letters Patent No. 374,665, dated December 13, 1887.

Application filed May 20, 1887. Serial No. 238,810. (No model.)

To all whom it may concern:

Be it known that I, HORACE ESTABROOK, a citizen of the United States, residing at Paterson, Passaic county, State of New Jersey, have 5 invented a new and useful Improvement in Railway-Scales, of which the following is a specification, reference being had to the accompanying drawings, forming a part thereof.

The anvil-blocks on the scale-platform for 10 supporting the free end of the bridge-rails and the springs for supporting the bridge-rails in their elevated position, hitherto employed when connecting the permanent railway-track rails with those of the railway-scale track, are 15 found to be objectionable on account of the clattering noise and excessive wear of the engaging parts. The car while passing over the bridge-rail forces the free ends of the same into contact with the anvil-blocks, to be raised 20 by the spring as soon as relieved from the pressure of the wheel that has passed, to be again depressed by each succeeding car-wheel as the train passes.

The object of my present invention is to so 25 connect the permanent railway-track with the railway-scale track as to secure the advantages of the anvil-blocks and springs without their objectionable features.

With these ends in view my invention consists in a railway-scale platform having rail 30 chairs or seats therein to receive and support the free end of the bridge-rails in a position always even with the railway-scale track.

My invention further consists in certain features of construction and combination of parts, 35 as will be hereinafter fully described, and pointed out in the claim.

Figure 1 of the drawings is a plan view of 40 my invention, in which figure the platform and track-rails are broken. Fig. 2 shows a portion of one side of the same in elevation.

A represents a railway-scale of any suitable construction, in the platform *b* of which scale I arrange and secure rail seats or chairs *D*. 45 The chairs or seats *D*, which are constructed of plates of wrought-iron, are provided with

upward-projecting lugs *F F'*. The lugs or guides *F F'* are riveted in the said wrought-iron plates and form a part of the chairs or seats *D*, and serve to guide the free end of the bridge-rail *B* in its vertical movement and hold the same in exact position with the platform-track rail *C* and prevent lateral displacement of said bridge-rail *B* and scale-track rail *C*. The chairs or seats *D*, which are bolted 50 to the platform *b*, are arranged to be even with the platform of the scales, so as to offer no obstruction and prevent dirt accumulating thereon.

The bridge rail or joint *B* is pivoted at one 60 end to the permanent rail *A'* by means of plates *E*, one of which is arranged on each side of the rails *A'* against the web thereof, and are secured in position thereon by bolts *E'*, while the bridge-rails *B* are pivoted on a 65 pivot-bolt, *E''*. The free ends of the bridge-rails *B* are adapted to rest on the rail seat or chair *D*, between the lugs *F'* of the same, and even with the rail *C* on the scale-platform *b*, as shown in Fig. 2.

By this my invention cars pass smoothly 70 from the permanent track *A'* over the bridge-rail *B* upon the scale-track *C*, causing no jar in passing, and pass without injury to the scale mechanism, while the scale-platform will 75 yield by depression to the several cars that pass, in accordance with their weight.

Having described my invention, I claim as new and desire to secure by Letters Patent in a railway-scale—

The combination, with a depressible platform having a track-rail, of a rail seat or chair having guides adapted to hold in position the end of the platform-track rail and guide the free end of the bridge-rail to its seat in said 85 chair and even with the track-rail therein, and bridge-rail *B*, adapted to seat in the said chair, as and for the purpose herein set forth.

HORACE ESTABROOK.
